DESIGN FOR A BABY SHOE

Evelyn M. Potts, Grand Ledge, Mich.

Application February 12, 1947, Serial No. 136,853

Term of patent 14 years

(Cl. D7—7)

To all whom it may concern:

Be it known that I, Evelyn M. Potts, a citizen of the United States, residing at Grand Ledge, in the county of Eaton and State of Michigan, have invented a new, original, and ornamental Design for a Baby Shoe, of which the following is a specification, reference being had to the accompanying drawings, forming a part thereof.

In the drawings—

I claim:

The ornamental design for a baby shoe, as shown.

EVELYN M. POTTS.
